UNITED STATES PATENT OFFICE

FRANK B. PETERS, OF MINNEAPOLIS, MINNESOTA

AUTOMATIC STORM SASH OPERATOR

Application filed February 13, 1931. Serial No. 515,508.

My invention relates to automatic storm sash operators of the type which connect a sliding sash to a swinging storm sash mounted in the same window frame, whereby the opening and closing movements of the sliding sash will impart like movements to the storm sash, thus avoiding the effort and inconvenience of opening and closing the storm sash, independent of the sliding sash.

10. The object of the invention is to provide a storm sash operator that is of simple construction, easy to attach to the respective sashes, positive in its action, will not rattle during relative movement of the sashes, and 15 that may be readily separated without the use of tools to permit the removal of the storm sash from the window frame.

Generally stated, the invention consists of the novel devices and combinations of devices hereinafter described and defined in the claims.

In the accompanying drawings, which illustrate the invention, like characters indicate like parts throughout the several views.

20 Referring to the drawings:

Fig. 1 is a fragmentary view principally in vertical section taken through a window frame in which is mounted upper and lower sliding sashes and a swinging storm sash 30 connected to the lower sliding sash by the improved sash operator;

Fig. 2 is a view corresponding to Fig. 1 with the exception that the lower sliding sash and swinging sash are partly open;

35 Fig. 3 is a fragmentary perspective view of the sash operator as shown in Fig. 2, on an enlarged scale;

Figs. 4 and 5 are fragmentary detail views with some parts sectioned on the lines 4-4 and 5-5, respectively, of Fig. 3;

40 Fig. 6 is a perspective view of the anchor plate; and

Fig. 7 is a perspective view of the actuator.

45 The numeral 8 indicates the frame of a double hung window, and the upper and lower sliding sashes thereof are indicated by the numerals 9 and 10, respectively. The storm sash 11 is mounted in the window frame 8 and attached thereto at its top by

suitable hinges 12 for outward swinging movement.

Two of the automatic operators are employed for the swinging sash 11, one at each side thereof, and only one of which is shown. 55 Each storm sash operator comprises a link 13, an anchor plate 14 and an actuator 15.

The anchor plate 14 is secured to one of the stiles of the storm sash 11 by a pair of wood screws, and has at its vertical center a 60 horizontally disposed sleeve-like bearing 16. A trunnion 17, formed by bending the upper end portion of the link laterally, is turnably mounted in the bearing 16. The trunnion is held against removal from the bearing 16 by a guard flange 18 formed with the anchor plate 14 and having a notch-like passageway 19 aligned with said bearing for the removal of the trunnion 17 therefrom when the link 13 is in a pre-determined relation thereto, to-wit: perpendicular to the anchor plate 14.

As shown, the actuator 15 comprises a base 20, a body member 21 having a cam slot 22 and cam flange or shoulder 23, and a guard flange 24 formed from a single sheet of metal. The base 20 is secured to one of the stiles of the lower sliding sash 11 by a pair of wood screws, and the body 21 is perpendicular to said base and in the plane of said sash. It 70 will be noted that the cam slot 22 is upwardly and outwardly inclined from the base 20, and the cam flange 23 overlies the cam slot 22 and is downwardly and inwardly inclined from said base, or in other words it is 75 reversely inclined from the cam slot 22. The guard flange 24 is perpendicular to the base 20 and laterally spaced from the body 21, on the same side thereof as the cam flange 23.

The link 13, at its lower end portion, is folded upon itself to form a cam finger 26 and between said link and cam finger a short pivot 25 which extends through the slot 22 for compound pivotal and sliding movements therein. This cam finger 26 and the link 13, which are on the opposite sides of the body 21, hold the pivot 25 in the cam slot 22.

The purpose of the guard 24 is to prevent 100

the pivot 25 from being forced laterally out of the slot 22 by the bending of the link 13 during pushing strains on said link by the actuator 15 to open the swinging sash 11.

- 6 A coil spring 27 encircling the link 13 has its upper end anchored to said link, and its other end attached by a straight end section 28 of said spring to the actuator 21 at a point below the cam slot 22. The spring section 28 is connected to the actuator 21 by a separable connection 29. This spring 27, when the sashes 10 and 11 are open, yieldingly holds the pivot 26 seated against the actuator at the lower end of the cam slot 22 and prevents rattle in the connection between the link 13 and actuator 21 when the sashes are open.

When the sashes 10 and 11 are closed, the pivot 26 is at a point intermediate of the ends of the cam slot 22, and the spring 27 is held under tension. This position of the pivot 26 in the cam slot 22 permits a limited opening and closing movement of the lower sash 10 when the swinging sash 11 is closed.

- 25 During the opening movement of the lower sash 10, the actuator 22 engages the pivot 26, and acting through the link 13 swings the storm sash 11 open. The spring 27, when the sashes 10 and 11 are open, prevents movement of the swinging sash 11 under the action of the wind.

During the closing movement of the sliding sash 10, the tension of the spring 27 is such as to hold the link 13 with its pivot 26 at the lower end of the cam slot 22, and thereby direct the cam finger 25 under the cam flange 23. At the time the swinging sash 11 reaches its closing movement, further closing movement of the sliding sash 10 will bring the cam flange 23 into engagement with the upper end of the cam finger 25 and thereby move said cam finger toward the sliding sash 11 about the axis of the pivot 26 which is held in the slot 22. This movement of the cam finger 25 bows the link 13 and places the same under strain to tightly draw the swinging sash 11 against the window stops and thereby securely hold the same closed.

The sash operator may be readily separated from the sliding sash 10 by bringing the cam finger 25 into registration with the cam slot 22 and then moving the same laterally therethrough after the spring section 28 has been detached from the actuator 21.

To remove the link 13 from the anchor plate 55 14, it is only necessary to bring said link into a perpendicular position in respect to said plate and then move the same laterally to withdraw the trunnion 17 from the bearing 16 and through the passageway 19.

60 From the above description it is evident that the actuator 21 is double-acting in that its action on the link 13 not only imparts opening and closing movements to the swinging sash during like movements of the sliding sash but it locks the swinging sash closed

during the final closing movement of the sliding sash.

What I claim is:

1. A device of the class described comprising a link having at each end a member applicable, the one to a swinging sash and the other to a sliding sash, said link having a slip joint that is oblique to the plane of the sliding sash and arranged to permit limited opening and closing movements of the sliding sash when the swinging sash is closed, said device having a part arranged to engage the link by lateral pressure during the final closing movement of the sliding sash and place the link under strain to hold the swinging sash closed. 70

2. The structure defined in claim 1, which further includes spring means under strain to hold the link at its slip joint in one extreme position. 75

3. A device of the class described comprising an anchor member applicable to a swinging sash, a link hingedly connected to said member, an actuating member applicable to a sliding sash, said link having a slip connection with the actuating member that is oblique to the plane of the sliding sash to permit limited opening and closing movements of the sliding sash when the swinging sash is closed, and a cam on the actuating member oblique to the plane of the sliding link and arranged to engage the link during the final closing movement of the sliding sash and place the same under strain to hold the swinging sash closed. 90

4. A device of the class described comprising an anchor member applicable to a swinging sash, a link, one end of which is hingedly connected to said member, an actuating member applicable to a sliding sash and having a slot oblique to the plane of the sliding sash and in which the other end of the link is mounted for compound pivotal and sliding movements, said slot being arranged to permit limited opening and closing movements of the sliding sash when the swinging sash is closed, and a cam on the actuating member, said link having a part arranged to be engaged by the cam during the final closing movement of the sliding sash to hold the swinging sash closed. 100

5. A device of the class described comprising an anchor member applicable to a swinging sash, a link, one end of which is hingedly connected to the anchor member, an actuating member applicable to a sliding sash and having a cam slot oblique to the plane of the sliding sash and in which the link is mounted for compound pivotal and sliding movements, said slot being arranged to permit limited opening and closing movements of the sliding sash when the swinging sash is closed, and a cam shoulder on the actuating member, said cam slot and cam shoulder being reversely inclined and oblique to the plane 110

of the sliding sash, said link having a part arranged to be engaged by the cam shoulder during the final closing movement of the sliding sash and place the link under strain to hold the swinging sash closed.

5 6. A device of the class described comprising an anchor member applicable to a swinging sash, a link, one end of which is hingedly connected to the anchor member, an actuating member applicable to a sliding sash and having a cam slot oblique to the plane of the sliding sash and a cam shoulder that are reversely inclined and oblique to the plane of the sliding sash, the other end portion of the link being folded upon itself to form a pivot and a lock finger, said pivot being mounted in the cam slot for compound pivotal and sliding movements, said slot being arranged to permit limited opening and closing movements of the sliding sash when the swinging sash is closed, said cam finger being arranged to be engaged by the cam shoulder during the final closing movements of the sliding sash and moved laterally thereby and place the link under strain to hold the swinging sash closed.

7. The structure defined in claim 6 which further includes a spring operative on the link to move its pivot in the cam slot in the direction of the closing movement of the swinging sash.

8. The structure defined in claim 6 which further includes a guard on the actuating member arranged to engage the cam finger and hold the pivot in the cam slot during opening and closing movements of the swinging sash.

In testimony whereof I affix my signature.

FRANK B. PETERS.
